UNITED STATES PATENT OFFICE.

JAMES A. SILSSEE, OF ELMIRA, NEW YORK.

INVENTION OF AUTOMATIC AIR-VALVE FOR ENGINE INTAKE-MANIFOLDS.

1,210,991.

Specification of Letters Patent.

Patented Jan. 2, 1917.

Application filed August 8, 1916. Serial No. 113,684.

To all whom it may concern:

Be it known that I, JAMES A. SILSSEE, a citizen of the United States, residing at Elmira, in the county of Chemung and State of New York, have invented certain new and useful Improvements in Automatic Air-Valves for Engine Intake-Manifolds, of which the following is a specification.

This invention relates to certain new and useful improvements in automatic air valves for engine intake manifolds.

The primary object of the invention is the provision of an air inlet arranged within the intake manifold of the gasolene engine between the carburetor and explosion chambers, a controlling device being provided for the entrance of air automatically varied and controlled by the speed of the motor to which the explosive mixture is being fed.

20 A further object of the invention is the provision of an attachment adapted for co-operation with any standard form of carburetor having an intake manifold leading therefrom to the explosive chamber whereby 25 varied amounts of air are fed into the manifold in amounts varying in proportion to the relative speed of the motor.

A still further object of the device is the provision of an auxiliary air intake for manifolds operable for the automatic dilution of the explosive mixture for the engine upon an increase of speed, thereby accomplishing a saving in gasolene and obtaining an equal amount of power by reason of the 35 improved quality of the combustible mixture for explosive purposes in the motor.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this 45 application and in which like designating characters refer to corresponding parts throughout the several views: Figure 1 is a side elevation of a four cylinder motor having the present device operatively attached thereto, illustrating one form of installation. Fig. 2 is an enlarged detail view of the automatic air valve employed with the device partially broken away. Fig. 3 is a front elevation of a portion of the air supply pipe. 50 Fig. 4 is a front elevation of the valve sleeve

employed. Fig. 5 is a central longitudinal sectional view of Fig. 2, and, Fig. 6 is a transverse sectional view taken upon line VI—VI of Fig. 2.

It being understood that the present automatically controlled auxiliary air intake is designed for employment with any form of internal combustion engine, such as that of an automobile, the device is herein illustrated mounted upon the upright 10 of the gasolene intake manifold 11 of a motor 12 having four cylinders 13 arranged in substantially the usual manner and provided with a water circulating manifold 14. The motor 12 is provided with an air circulating fan 15 mounted upon a fan shaft or axle 16 operatively connected to the crank shaft (not shown) of the motor by means of a driving belt 17.

The present attachment is readily tapped into the manifold 11 at any desired point, such as the upright 10 thereof, it being understood that the device is positioned at any point between the carburetor (not shown) and the cylinders 13. An angular pipe 18 is mounted upon the manifold upright 10, being provided with a manually operable turn-off valve 19 while the said pipe is provided with a pear-shaped air inlet or valve port 20. A valve sleeve 21 is longitudinally slidably mounted upon the pipe 18 by means of a screw 22 carried by the said pipe and arranged within a longitudinal slot 23 in the said sleeve permitting a limited longitudinal movement of the latter while preventing any relative rotation of the same. The sleeve 21 is provided with a circular air inlet or port 24 normally out of alignment with the pear-shaped port 20 when the sleeve is in its lowered position, the length of the slot 23 allowing the sleeve 21 to be elevated sufficiently to allow the upper edges of the ports 20 and 24 to be in alignment with each other, admitting a maximum amount of air into the pipe 18. The length of the slot 23 is sufficient to allow the longitudinal movement of the sleeve 21 to position the port 24 thereof slightly beneath the pear-shaped port 20 when the sleeve is lowered when the valve is closed, and to be elevated to position the port 24 to substantially open the entire port 20 when the sleeve is elevated, it being understood that the action of the sleeve 21 is unaffected by suction. A grooved collar 25 is adjustably secured to

the sleeve 21 as by means of a set screw 26 while a band 27 is revolably journaled in the annular groove 28 of the said sleeve.

A cylindrical head 29 is screw-threaded 5 upon the upper end of the pipe 18 closing the same while a pulley wheel or disk 30 forming a part of an automatic governor for the valve sleeve 21 is journaled upon an upper extension of the said head, being retained thereon by means of a nut 31 removably secured thereto. The arms 32 of a centrifugal governor are pivoted to the under side of the disk 30 and the opposite sides of the band 26, the balls or weights 15 33 for the governor being pivoted between the inner ends of the pairs of arms 32 in substantially the usual manner.

It is to be noted that the governor is to be 20 operatively attached to any rotating part of the motor in any desired manner such as by means of a belt, gears, universal joints, flexible shafts, direct connections and the like. For purposes of illustration, one 25 form is here shown. A pulley wheel 34 is secured to the fan shaft 16 over which a round belt or cord 35 is arranged operatively connecting the wheel 34 with the disk 30, it being understood that idlers 36 and 37 may be employed for the belt 35 at convenient 30 points if found desirable.

From this detailed description of the invention it will be seen that the same may be readily attached to the intake manifold of any engine and that the automatic operating governor 38 thereof may be connected 35 in any manner for being controlled by the speed of the motor whereby the port 20 being closed when the motor is at rest, the same will be gradually opened by means of 40 the port 24 of the sleeve 21 as the speed of the motor increases, operating the governor 38 to gradually elevate the valve sleeve 21.

This device is not a carbureter nor an attachment to a carbureter but is designed to 45 work in coöperation with any standard carbureter in general use and is completely shown by the accompanying drawing though all the details of its construction as shown need not be strictly adhered to, but such 50 changes may be made as may be found necessary for manufacture or operation.

The pipe 18 forms both the governor shaft and one of the sleeves of the sleeve valve and is fitted with the said valve 19 which 55 may be entirely closed from time to time when it is necessary to adjust the carbureter (as this could not be done with the device working), or which may be partially closed if necessary to reduce the amount of air 60 entering the engine in cold weather. This may be done by suitable levers from the driver's seat or by raising the hood. Besides this valve 19, the pipe may be made up of any number of fittings such as elbows, 65 nipples, unions and couplings, which may

be found convenient for attaching to the engine or for wrapping around the exhaust pipe to heat the air before entering the engine. The remainder of the device consisting of a centrifugal governor is connected 70 to the most accessible rotating part of the engine either by belt, bevel gears, friction gears, universal joints or flexible shaft or direct connections for automatically operating the sliding sleeve valve varying the 75 quantity of air admitted depending on the speed of the engine and governor. This sleeve may also be made up with any packings or piston rings which may be found necessary to prevent leakage. Also the closing action of the governor may be controlled 80 by suitable springs instead of by gravity so that if more convenient, it may be attached in a horizontal position instead of vertical as shown.

The attachment and action of the device is as follows: Assuming that the lower end of the pipe 18 has been tapped into the manifold 10 and the governor connected to a moving part of the engine, unscrew the 90 set screw 26 and start the motor at a speed which is sufficient to drive the vehicle about ten miles per hour, or at a moderate speed at which it runs smoothly without skipping. When this has been done, slide the valve 95 21 up by hand until the top of the round hole 24 is just at the point of the pear-shaped hole 20 and at the same time note the position of the collar 25 relative to the sleeve 21 and clamp them together in this position. This may be done by one or more set screws 26 or by having the collar threaded to the sleeve. As the motor and consequently the governor gradually take on greater speed, the governor balls 33 will 100 spread wider apart raising the sleeve 21 and gradually bringing the holes 20 and 24 one above the other, admitting air through the pipe 18 to the manifold, and when the motor slows down as for a rough road or crossing a railroad, the valve will close giving the motor a rich mixture so that it 110 will not stall. The principle of this device is to automatically dilute the explosive gas of an engine, with air at speeds which permit it, thereby using less gasoline for an 115 equal amount of power.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:—

1. A device of the class described comprising in combination with an explosive motor having a gasoline intake provided with an upright, an angular pipe tapped into said 130

upright and having a pear-shaped air inlet opening in the side thereof, a sleeve longitudinally slideable upon the said pipe having a circular air port therein adapted for registry with the said opening, pin and slot connections between the said sleeve and pipe whereby the said port and opening are out of alinement when the sleeve is in its lowered position and are in open alinement with each other when the sleeve is elevated, a head upon the said pipe, a disk journaled upon the said head, a collar adjustably mounted upon the said sleeve, a band revolvably journaled upon the said collar, and weighted governor members pivotally linked between the said disk and band.

2. A device of the class described, comprising in combination with an explosive motor having a gasolene intake provided with an upright, an angular pipe tapped into said upright and having a pear-shaped air inlet opening in the side thereof, a sleeve longitudinally slideable upon the said pipe having a circular air port therein adapted for registry with the said opening, pin and slot connections between the said sleeve and pipe whereby the said port and opening are out of alinement when the sleeve is in its lowered position and are in open alinement with each other when the sleeve is elevated, a head upon the said pipe, a disk journaled upon the said head, a collar adjustably mounted upon the said sleeve, a band revolvably journaled upon the said collar, weighted governor members pivotally linked between the said disk and band, and operative connections between the said disk and motor whereby the said port and opening are gradually brought into registry with each other during the increased speed of the motor.

In testimony whereof I affix my signature.

lubly journaled upon the said collar, weighted governor members pivotally linked between the said disk and band, and operative connections between said governor and a rotating part of the motor.

3. A device of the class described comprising in combination with an explosive motor having a gasolene intake provided with an upright, an angular pipe tapped into said upright and having a pear-shaped air inlet opening in the side thereof, a sleeve longitudinally slideable upon the said pipe having a circular air port therein adapted for registry with the said opening, pin and slot connections between the said sleeves and pipe whereby the said port and opening are out of alinement when the sleeve is in its lowered position and are in open alinement with each other when the sleeve is elevated, a head upon the said pipe, a disk journaled upon the said head, a collar adjustably mounted upon the said sleeve, a band revolvably journaled upon the said collar, weighted governor members pivotally linked between the said disk and band, and operative connections between the said disk and motor whereby the said port and opening are gradually brought into registry with each other during the increased speed of the motor.

JAMES A. SILSBEY.
